UNITED STATES PATENT OFFICE.

FRANK F. SCHLUETER, OF WATERTOWN, WISCONSIN.

DENTAL DRILL.

1,321,130.

Specification of Letters Patent.

Patented Nov. 11, 1919.

Application filed February 20, 1919. Serial No. 278,232.

To all whom it may concern:

Be it known that I, FRANK F. SCHLUETER, a citizen of the United States, residing at Watertown, county of Jefferson, and State 5 of Wisconsin, have invented new and useful Improvements in Dental Drills, of which the following is a specification.

My invention relates to improvements in paralleling attachments for dental drills, 10 this application being a companion application, co-pending with one filed by me December 24th, 1918, Serial No. 266904, under a like title.

The object of the present invention is to 15 provide means, whereby the gage post or pin may be brought into close proximity with a drill or other tool,—to provide means, whereby a drill or grinding wheel may be moved from one position to another while 20 the paralleling post remains fixed, or anchored, in a previously formed socket within which it merely oscillates about its own axis during the movements of the drill or other tool from one point of operation to another,—to further provide means whereby a 25 tool employed for cutting away the surface of a tooth may be moved in a circle, or along a curved line, and its movements so controlled as to cut a cylindrical or other curved 30 surface, all vertical lines of which are parallel with the axis of the gage pin when anchored in a previously formed socket more or less distant from the field of cutting operations,—and to provide more convenient means than that described in said 35 former application for varying the distance between the gage pin and the cutting tool to suit the requirements of the work.

In the drawings:—

40 Figure 1 is a side elevation of a dental drill and its holder, with my attachment applied thereto, the holder and drill actuating connections being of that type in which the body of the holder is at right 45 angles to the axis of the drill.

Fig. 2 is a plan view of the same, with dotted lines indicating different positions of tool adjustment possible with the gage post anchored in a single socket.

50 Fig. 3 is a cross section, enlarged, on line 3—3 of Fig. 1.

Like parts are identified by the same reference characters throughout the several views.

55 The drill holder A is of a common type of construction, in which the drill B is sup-

ported at right angles to the body of the holder, the driving connections being such as to actuate the drill in this position. Such drills being in common use, further description thereof is deemed unnecessary, except that I prefer to provide the drill holder with a nose piece or chuck 1, having a neck 2 of reduced size, and adapted to receive a forked clamping member having resilient arms 3 60 and 4, grooved on their inner faces to receive the neck 2. The extremities of the arms have beveled inner faces, as indicated at 6, whereby they may be pushed into position of engagement with the neck 2, the arms 65 spreading resiliently until the neck is received in the grooves 7, whereupon the arms spring together sufficiently to clampingly engage the neck in this position.

This forked clamping member has its 70 outer end pivotally connected by a bolt 9 with an arm 10, having a vertically disposed socketed head 11, in which a slide 12 seats. The head 11 is open at the bottom, and the slide 12 may be pushed upwardly into this 75 socket, against the pressure of a coiled spring 13 seated in the upper end of the socket. A spring actuated latch 14 is secured to the outer surface of the head, and provided with an elbowed portion 15, which 80 passes through an aperture near the lower end of the head, and engages a reduced portion of the slide. This reduced portion of the slide may be formed by merely cutting away a portion of the slide which may be 85 circular or cylindrical in form. The elbowed extremity 15 of the spring 14 serves to limit the vertical movements of the slide.

At the lower end of the slide, I provide a laterally projecting arm 20, which is el- 90 bowed to provide a vertical post 21, adapted to enter the socket formed in a tooth or in the root of a tooth, and to serve as an anchor post, and also as a paralleling gage post to control the position of the drill B, whereby 95 the latter will drill a vertical hole parallel with the socket in which post 21 is anchored, and whereby a cutting tool substituted for the drill B may be employed to cut surfaces having vertical lines parallel with the 100 post 21.

The pivot post at 9 is also parallel with the gage post 21, and occupies a vertical position in normal operations. This post permits the clamping fork 3—4 to swing in 105 coöperation with the arm 10, so as to increase or diminish the distance between the

2
drill and the post 21, and to allow the drill to be moved bodily in any direction within a plane at right angles to post 21. That is to say, the drill may be moved freely in any direction, which does not require it to be tilted out of a position parallel with the post 21.

The arm 20 allows the post 21 to be offset sufficiently from the slide 12 and if desired 10 this post may be brought into close proximity to the drill by turning the slide 12, so that arm 20 projects toward the drill, and by folding the clamping member 3-4, and the arm 10, one upon the other, to one of the 15 positions indicated by dotted lines in Fig. 2. In this manner, it is possible to anchor the post 21 in a socket as close to the drill B as may be required for any dental operation, it being obvious that the post may be anchored in a tooth cavity, and the cutting tool 20 operated to cut away the outer surface of the same tooth. Slides 12 may be provided, having arms 20 of varying length, whereby the extent to which the post 21 is offset may 25 be varied, as required.

I claim:—

1. An attachment for dental drills comprising a forked clamping member adapted to clampingly engage the nose piece of a 30 drill holder for swinging movement thereon, a gage pin, and a supporting connection between the gage pin and the forked clamping member.

2. An attachment for dental drills comprising a forked member adapted to clampingly engage the nose piece of a drill holder for swinging movement thereon, a gage pin, and a connecting member supporting the 40 gage pin in vertically movable relation to the clamping member.

3. An attachment for dental drills comprising the combination of a member adapted to be detachably connected with a drill holder, and to project laterally therefrom, 45 an arm pivoted to said member, and adapted to swing in a plane transverse to the drill holder axis, and a gage pin supported from the swinging end of said arm in a position parallel with a drill carried by the drill 50 holder.

4. An attachment for dental drills comprising the combination of a member adapted to be detachably connected with a drill holder, and to project laterally therefrom, 55 an arm pivoted to said member, and adapted to swing in a plane transverse to the drill holder axis, and a gage pin supported from the swinging end of said arm in a position parallel with a drill carried by the drill 60 holder, and in resiliently yielding relation to said arm along the line of its own axis.

5. An attachment for dental drills, com-

prising the combination of two pivotally connected members, and a gage pin secured to one member, the other member having 65 means for detachably connecting it with a drill holder.

6. In an attachment for dental drills, a gage pin having its lower portion offset from its upper portion, and means for supporting the pin with its lower end parallel with the drill with which it is associated. 70

7. An attachment for dental drills, comprising the combination of a drill holder, a detachable laterally projecting arm therefor, and a gage pin operatively connected with said arm and having an offset lower end. 75

8. An attachment for dental drills, comprising the combination of a drill holder, a detachable laterally projecting arm therefor, and a gage pin operatively connected with said arm and having an offset lower end, said gage pin being rotatively adjustable upon its connection with said arm. 80 85

9. An attachment for dental drills, comprising the combination of a drill holder, a detachable laterally projecting arm therefor, and a gage pin operatively connected with said arm, and having an offset lower end, said gage pin being rotatively adjustable upon its connection with said arm, and also adapted to resiliently yield along the axial line of its offset lower end. 90

10. An attachment for dental drills, comprising the combination of a drill holder, a detachable laterally projecting arm therefor, and a gage pin operatively connected with said arm and having an offset lower end, said gage pin being rotatively adjustable upon its connection with said arm, and said arm having an intermediate joint, the axis of which is parallel to the axis of the lower end of the pin. 95

11. An attachment for dental drills, comprising the combination of a drill holder, a detachable laterally projecting arm therefor, and a gage pin operatively connected with said arm and having an offset lower end, said gage pin being rotatively adjustable upon its connection with said arm, and said arm having an intermediate joint, the axis of which is parallel to the axis of the lower end of the pin, and being also rotatably adjustable about the drill holder on 110 an axis of rotation coinciding with the drill, and parallel with said other axes. 115

In testimony whereof I affix my signature in the presence of two witnesses.
